(57) **CLAIM**

The ornamental design for a handheld drug delivery device, as shown and described.

DESCRIPTION

This patent or application file contains a least one drawing executed partly in color. Copies of this patent or patent application publication with drawing(s) partly in color will be provided by the Office upon request and payment of any necessary fee.

FIG. 1 is a perspective view showing a first embodiment of a new design for a handheld drug delivery device;

FIG. 2 is a front view of the handheld drug delivery device of FIG. 1;

FIG. 3 is a rear view of the handheld drug delivery device of FIG. 1;

FIG. 4 is a right-side view of the handheld drug delivery device of FIG. 1;

FIG. 5 is a left-side view of the handheld drug delivery device of FIG. 1;

FIG. 6 is a top view of the handheld drug delivery device of FIG. 1;

FIG. 7 is a bottom view of the handheld drug delivery device of FIG. 1;

FIG. 8 is a perspective view of the handheld drug delivery device of FIG. 1 with its cap removed; and,

FIG. 9 is a top view of the handheld drug delivery device of FIG. 1 with its cap removed.

The broken line areas of the handheld drug delivery device are included for the purpose of illustrating environment and form no part of the claimed design.

Those portions of the drawings that are not shown in color are intended to encompass designs where those portions are of any color, or are clear, transparent, opaque, or otherwise.
